UNITED STATES PATENT OFFICE.

GEORGE DUESLER, OF GLENDALE, CALIFORNIA, ASSIGNOR TO INTERNATIONAL MOTOR COMPANY, OF NEW YORK, N. Y., A CORPORATION OF DELAWARE.

DETACHABLE HOSE TRAY.

Application filed March 14, 1928. Serial No. 261,505.

The present invention relates to devices for carrying hose upon a motor vehicle, particularly of the fire truck type. It is frequently desirable, in time of fire, to carry 5 a length of hose with fittings attached and ready for service bodily to a given position, or remove it from the truck, quickly and with very little difficulty. Heretofore, the rear of the hose wagon has been provided with 10 a body having an open end, from the step of which firemen have access to the length of hose carried in the body. In removing the hose quickly, care must be taken to avoid tangling thereof and considerable time is 15 consumed. This invention has for an object, the provision of a tray for receiving hose, the tray being carried by a remote portion of the vehicle so that the capacity of the hose body itself is not decreased, and the tray will 20 be available for service by a very slight operation of suitable controls.

A further object of the invention is to mount a hose tray upon a vehicle in a manner such that it may be easily dropped from a 25 vehicle while the latter is moved without injuring the tray. The particular manner of mounting the tray is by means of tracks engaged by rollers carried by the tray. By giving the tracks a rearward and downward 30 slant, the tray, when released, rolls down the tracks and is deposited upon the ground with only a very slight fall.

The invention will be understood more fully from the accompanying drawings, 35 wherein:

Figure 1 is a plan view, partly in section, taken on line 1—1 of Figure 2 and looking in the direction of the arrows.

Figure 2 is a view, in section, taken on 40 line 2—2 of Figure 1 and looking in the direction of the arrows.

Figure 3 is a view in section, taken on line 3—3 of Figure 1 and looking in the direction of the arrows.

45 Referring to the drawings, *a* designates the rear axle and drive of a motor vehicle of the fire truck type carrying side frame members *a'*. The usual flooring of the hose wagon is shown at *b*, the sides at *c*, and the 50 hand rail at *d*. A rear step *e* is provided for the usual purposes and the present invention is incorporated in this existing structure in the following manner.

Secured to the side frame members at

spaced points on either sides of the vehicle, 55 are tracks *f*, *g*, *f'* and *g'*. Tracks *f* and *f'* are mounted above the respective tracks *g* and *g'*, although the upper ends of all the tracks are mounted at the same level upon the side frame members *a'*. The tracks *f* and *f'* slope abruptly downwardly to the 60 under portion of the step *e*, upon which all of the tracks are mounted at *e'*. The tracks *g* and *g'* slope gradually from the side frame members to the forward portion of the step 65 as shown clearly in Figure 2. The tracks are formed of angle members although the portions of the tracks *f* which slope abruptly downwardly are preferably provided with a protective flange to prevent the rollers 70 from jumping the tracks. A tray *h*, of suitable dimensions, is provided at its four corners with rollers *h'* mounted upon brackets *h*² which are secured to angle members *h*³ extending around the inner rim of the 75 hose tray *h*. It will be seen that the rollers *h'* will engage the respective tracks and carry the tray under the vehicle frame in such manner that it may be readily removed. The rear end of the tray is provided with 80 handles *h*⁴ to facilitate moving the tray and strengthening strips *h*⁵ may be provided on the under side thereof to increase its strength.

When the tray is to be inserted the rear rollers *h'* are inserted in the respective 85 tracks *g* and *g'* and the tray slid forward until the rear rollers *h'* are ready to engage tracks *f* and *f'*. The tray is then slid into the position shown in dot and dash lines in Figure 2 at which time trap door *e*² is raised 90 in order that the handles *h*⁴ may be grasped to lift the tray into the position shown in full lines in Figure 2.

A shaft *i* is mounted at the rear of the frame and carries a ratchet wheel *i'* and 95 pawl *i*². Operating lever *i*³ permits the shaft to be turned, causing link *i*⁴ to move lever *i*⁵, pivoted at *i*⁶ to the bottom of the flooring *b*. Movement of lever *i*⁵ in a clockwise direction starts the tray *h* on its downward 100 movement, and after the rear rollers *h'* start down the incline of tracks *f* and *f'*, sufficient impetus is given the tray to carry it out of the tracks and cause it to be deposited upon the ground in back of the step *e*. A dog *i*⁷ carried upon the shaft *i*, engages the rear 105 of the tray to hold it in its nested position within the frame. It will be seen that the

dog i^7 is removed simultaneously with the movement of lever i^5 to permit the tray to be discharged.

The dimensions of the tray are such that the drop from the level of the tracks to the ground is very slight, thus reducing the wear upon the tray considerably and aiding materially in the dropping of the tray when the vehicle is traveling over the road. It has been found that the tray can be dropped with the vehicle traveling at from fifteen to twenty-five miles an hour without failure.

The specific dimensions, or arrangements of parts may be varied to suit fire trucks and hose wagons of different types and the invention is not to be limited, save as defined in the appended claims.

I claim as my invention:

1. A vehicle frame, a hose tray, front and rear guide members mounted at either side and at the top of the tray, individual tracks mounted parallel to the frame members and receiving the guide members, one of said tracks being inclined a greater amount than the other, and means to hold the tray at the top of the inclined tracks in a concealed position.

2. A vehicle frame including side frame members, a hose tray, tracks rearward of the rear axle mounted longitudinally of the frame and spaced between the side frame members, inclines formed in the tracks from the frame members to a discharging position, and means to hold the tray at the top of the inclines.

tion, and means to hold the tray at the top of the inclines.

3. A vehicle frame including side frame members, a body thereon including a rear step, a hose tray, tracks mounted longitudinally of the frame and carried by each side frame member and the step, inclines formed in the tracks from the frame members to the step, and means to hold the tray in a concealed position at the top of the inclines.

4. A vehicle frame including side frame members, a body thereon including a rear step, a hose tray, tracks mounted longitudinally of the frame and carried by each side frame member and the step, inclines formed in the tracks from the frame members to the step, an aperture between the step and body to provide access to the tray, and means to hold the tray in a concealed position at the top of the inclines.

5. A vehicle frame including side frame members, a hose tray, tracks mounted longitudinally of the frame and spaced between the side frame members at the rear thereof, said tracks being rearward of the rear axle and mounted one above the other at either side of the frame, inclines formed in the tracks from the frame members to a discharging position, and means to hold the tray at the top of the inclines.

This specification signed this 20th day of February A. D. 1928.

GEORGE DUESLER.
